UNITED STATES PATENT OFFICE.

DAVID F. CRAWFORD, OF PITTSBURGH, PENNSYLVANIA.

BLOCK-SIGNAL.

1,241,927.

Specification of Letters Patent.

Patented Oct. 2, 1917.

Application filed July 29, 1914, Serial No. 853,790. Renewed March 7, 1917. Serial No. 153,170.

To all whom it may concern:

Be it known that I, DAVID F. CRAWFORD, a citizen of the United States, residing at Pittsburgh, in the county of Allegheny and

5 State of Pennsylvania, have invented certain new and useful Improvements in Block-Signals, of which the following is a specification.

This invention relates to block signals for 10 railway service wherein a series of semaphores are stationed at intervals along the railway for the purpose of signaling to the trainmen.

My invention broadly contemplates the 15 provision of improved means for identifying the various signals along railways so that lamps used for illuminating streets, crossings, etc., adjacent the railways will not be mistaken for clear signal lamps located in the semaphores, the clear signal in the semaphore being caused to flicker or wink at regular intervals.

The invention further contemplates the 20 provision of a semaphore wherein the white or clear signal is the only light which is interrupted at intervals while the danger or colored signals are caused to be illuminated with a continuous light. With this arrangement should a colored signal lens become 25 dislodged or broken the light which illuminated the signal would appear white like a clear signal but as the illumination is continuous it indicates a danger signal regardless of its color for the reason that the light 30 is continuous and not flickering as it should be to indicate a clear track.

Among the more specific objects of my 35 invention are the provision of improved means for controlling the lights of a series of semaphore signals from a single point; the provision of an electric current system whereby a single light in a semaphore may at different times be illuminated through a plurality of current circuits; and the provision of means for changing the circuits 40 actuated by the movement of the semaphore arm when a signal is changed.

The foregoing together with such other 45 objects which may hereinafter appear or are incidental to my invention, I attain by means of a construction which I have shown in the accompanying drawing, the figure being a diagrammatic elevation of a series 50 of semaphores and the various electric circuits connecting the lamps of the sema-

phores with the source of power, together with circuit breaker or interrupter and switches used in following out the purpose of my invention.

In the figure, 1, 2, 3 and 4 designate a 60 series of semaphores and 5, 6, 7 and 8 indicate their respective semaphore arms or blades which are pivoted at 9 to the upright standards 10. One end of each blade is provided with a wing 11 in which is mounted 65 at equal distance from the pivot 9, a series of colored signal lenses marked R, G, and W indicating red, green and white or clear respectively.

The lenses are so positioned on the wing 70 11 that they may be brought to successively align with a signal lamp 12 which is mounted on the standard 10 in such manner that the light rays from the lamp may be directed 75 through the various lenses as they are brought into proper position.

The semaphore arms are actuated to bring the different lenses into alignment with the lamp by the solenoids 10' or some other form of operating means and are caused to 80 assume the position shown in semaphores 1, 2, and 3 by the rod 10" connecting the solenoid with the semaphore arm. The solenoids are energized from any suitable source 85 of electric current.

The electric lamp 12 is supplied with electricity from a battery 13 or any other convenient source of power by means of the 90 following wiring. A feed wire 14 leading from the positive pole of the battery extends the length of the system and from which the branches 14' extend to the contacts 15 on the switches 16 at each semaphore. A second feed wire 17 (shown in dotted lines) leading from the positive pole 95 of the battery 13 also extends the length of the system and from which, branches 17' connected thereto lead to the contacts 18 on the switches 16. Each lamp 12 is supplied with current through the leads 19 connecting contacts 20 on the switches 16 with the main negative return wire 21.

Feed wire 17 is provided with an interrupter 22 comprising a commutator ring 23 having suitable insulated contacts thereon 105 with which to make and break the circuits as the ring is rotated by the motor 24 to which the commutator is geared or otherwise connected. Motor 24 is supplied with current from the battery 13 through wire 110

25 and 26 secured to the binding posts 27 and 28 respectively and is maintained in continuous operation.

Switch 16 is provided with the switch bar 29 serving to connect contact 18 with contact 20 when the bar is in raised position as shown in semaphores 1 and 4, and contacts 15 and 20 are connected when the bar is in the lower position as shown in semaphores 10 2 and 3.

The switch bar 29 is operated by the movement of the semaphore arm by means of the connecting rod 30 which is pivoted to the arm at 31 and is so arranged that when 15 the semaphore arm is down the switch bar 29 is in the raised position. The current from the battery will then pass through the following circuit:—positive pole of battery 13, feed wire 17 (dotted line), interrupter 22, 20 feed 17, branch 17' contact 18, switch bar 29, contact 20, line 19, through the lamp 12, line 19 negative return line 21 to negative pole of the battery. The dropped position of the semaphore arm as in semaphores 1 25 and 4 indicates a clear block ahead and at this position of the arm a clear glass lens is alined with the lamp which is, at this time, receiving current through feed wire 17 having the interrupter disposed therein between the battery and the lamp thus causing the 30 lamp to flash light through the signal lens W at uniform intervals.

The purpose of causing the clear signal to be illuminated intermittently, as has previously been stated, is to identify the clear signal light from other white lamps adjacent the railway such as arc and gas lamps for illuminating streets, etc., and to identify the signals on the semaphore should the 40 colored signals be dislodged or broken.

When the semaphore arms are raised to the positions shown in semaphores 2 and 3 the switch bar 29 for each switch is pushed down out of engagement with contact 18, 45 and into engagement with contact 15 thereby connecting it with contact 20. At this time the green lens G in semaphore 2 and the red lens R in semaphore 3 are in alinement with their respective lamps, the green 50 signal indicating that the train proceed with caution, while the red signal indicates that the train must be stopped.

When the semaphore arms are in the positions shown in semaphores 2 and 3 the 55 current from the battery follows the circuit leading from the positive pole of the battery through feed wire 14, branch wires 14' switch contacts 15, switch bars 29, contacts 20, wires 19, lamps 12, wires 19 and through 60 the main negative return wire 21 to the negative pole of the battery 13. Negative return wire 21 is common to both circuits as well as the wire 19, and the switch 16 serves to connect the above wires with either 65 the feed wire 14 through branches 14' or

the feed wire 17 having the interrupter therein, through branches 17'.

The operation of the signal system for the semaphores is as follows:—

The battery 13 supplies current to the motor 24 serving to operate it continuously to rotate the commutator 23 of the interrupter 22, thus causing the lamp 12 to emit periodical flashes of light when the clear signal in the semaphore arm is brought into alinement with the lamp. The period of interruption to the light is preferably adjusted at the commutator so that a light of a tenth second duration will flash every nine-tenths of a second causing the period of a flash and interval to consume one second of time.

When the semaphore arm is down as in semaphores 1 and 4 the rod 30 has pulled the switch bar 29 into engagement with contacts 18 and 20 causing current to pass from the battery through the circuit interrupter 22 to the lamp, thereby causing the lamp to flash light at the intervals that the brushes 17'' are in contact with the connecting contacts of the commutator ring 23.

When the semaphore arm is raised to the green signal position as shown in the semaphore 2, the rod 30 has pushed down the switch bar 29 thereby connecting contact 15 with contact 20 and closing a circuit from the battery including feed wire 14 which has no interrupter in connection therewith and consequently the lamp shines continuously when a green signal lens is alined therewith. Raising the semaphore arm to the position shown in semaphore 3 wherein the red signal lens is alined with the lamp, does not alter the relation of the switch bar 29 with respect to the contacts 15 and 20 and therefore the lamp continues to burn steadily when the red signal is alined with the lamp.

In showing a series of semaphores having arms operating in the lower quadrant or below the horizontal position, I do not intend to limit my invention to such semaphores, as the features of my invention are applicable to various forms of semaphores and signaling apparatus. My invention includes any form of semaphore in which one or more of the lamps or signals are caused to flicker or be intermittently illuminated so as to identify the signal from a signal in the semaphore which shines or is illuminated continuously.

It will be evident that there are a number of means whereby the lamps or signals may be caused to wink or flicker, other than the specific means herein illustrated and described in disclosing my invention, and such means could be employed without departing from the spirit of my invention.

What I claim is:

1. In a semaphore, an electric lamp, a semaphore arm, signals carried by the said

5 arm adapted to be illuminated by the electric lamp, means for moving the semaphore arm to bring the different signals into operative illuminated position, a source of electric current for the lamp, and means controlled by the semaphore arm for intermittently interrupting the current to the lamp.

10 2. In a semaphore, an electric lamp, a semaphore arm, a plurality of signals carried by the said arm adapted to be illuminated by the electric lamp, means for moving the semaphore arm whereby the different signals are brought into operative illuminated position, a source of current, a lamp 15 circuit, an intermittent circuit interrupter in the lamp circuit between the current source and the lamp, and means whereby the actuation of the semaphore arm to bring a signal into operative position disconnects the circuit interrupter from the lamp circuit.

20 3. In a signal system, a series of semaphores, an electric main circuit comprising a current source, a positive feed wire extending to the semaphores, a negative return wire extending to the semaphores, an auxiliary positive feed wire extending to the semaphores, a lamp circuit for each semaphore having a lamp therein connected to the negative return wire, an intermittent 25 circuit interrupter in the positive feed wire between the current source and the lamp circuits, a switch for connecting alternately the positive feed wire and the auxiliary feed wire to the lamp circuit, a semaphore arm 30 on each semaphore, signals carried on such arm adapted to be brought into operative illuminated position by the movement of the said arm, operating means for the arm, and means whereby the operation of such means 35 to cause a signal to be brought into operative position operates the switch to change the connection of the positive feeds with the lamp circuit.

40 4. A railway signal system comprising a plurality of signal stations each provided with electrically operated signals arranged at spaced intervals along the railway, a source of electrical power, two separate cir-

50 cuits connecting the power source with a signal of each signal station, an intermittent circuit interrupter in one of the circuits for interrupting the power in that circuit whereby the signals are intermittently interrupted in their action synchronously with the interrupter, when the signal is supplied with power through that circuit, and a switch connecting either circuit with the signals.

55 5. A railway signal system comprising a plurality of signal stations each provided with electrically operated signals arranged at spaced intervals along the railway, a source of electrical power, two separate circuits connecting the power source with a signal of each signal station, an intermittent circuit interrupter in one of the circuits for interrupting the power in that circuit whereby the signals are intermittently interrupted in their action synchronously with the interrupter, when the signal is supplied with power through that circuit, and a switch connecting either circuit with the signals.

60 6. A railway signal system comprising a plurality of electrically operated signals arranged at spaced intervals along the railway, an electric power circuit extending from one end of the system to the other, a source of power connected with the circuit, connections from the signals connected with the power circuit so that the signals may be 65 operated by current from the same power source, and an intermittent circuit interrupter in the power circuit for interrupting the power in the power circuit whereby the signals are intermittently interrupted in their action synchronously with the interrupter.

70 In testimony whereof I have hereunto signed my name in the presence of the two 75 subscribed witnesses.
